ATTORNEY

UNITED STATES PATENT OFFICE.

GILBERT R. MILLER, OF BUTLER, PENNSYLVANIA.

VALVE-REGULATOR.

No. 918,072.

Specification of Letters Patent. Patented April 13, 1909.

Application filed April 16, 1908. Serial No. 427,303.

To all whom it may concern:

Be it known that I, GILBERT R. MILLER, a citizen of the United States, residing at Butler, in the county of Butler and State 5 of Pennsylvania, have invented certain new and useful Improvements in Valve-Regulators; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 My invention relates to certain new and useful improvements in valves, being more particularly applicable to the rotary class of valves.

The primary object involved in my invention, and which I propose carrying out in the following described manner, is the adaptation of a device whereby the valve, which controls the admission of gas, or other similar fuel, to the engine, can be so regulated, and adjusted, that the minimum and maximum quantity of gas passing therethrough is under the control of the engineer at all times, and under all conditions; even though the said engineer is stationed some 30 distance away from the engine house.

Another feature involved is the double adjusting means for regulating the movement of the operating lever.

These features, above enumerated, will be 35 of great advantage in oil and gas well drilling, or in fact any similar undertaking where it becomes necessary to regulate the supply of gas when the engine is running light or under load, and when the operator 40 is at some distance from the engine room.

In the accompanying drawing, forming a part of this specification, I have shown several detail views of my invention: Figure 1 being a front view in elevation; Fig. 2 a 45 similar view with the dial plate adjusted at an angle; Fig. 3 a side elevation partly in section.

Throughout the drawings numerals of reference designate like parts, in which the 50 numeral 1 is an ordinary straight-way valve casing in which is operatively seated the valve stem 2, having the V-shaped notch 3 formed therein. The formation of this valve is not an essential part of my invention, but is used as a convenient adjunct to 55 the more particular features which follow.

In the form shown in Figs. 1, 2, and 3, the casing 1 is provided at one side with an integrally formed bearing and securing plate 4, in contact therewith being the dial 60 plate 5, having formed thereon a graduated scale 6. This said plate is provided with arcuate slots 7—7, through which, and likewise through the plate 4, seat the securing bolts 8. The central portion of the plate 5 65 is also provided with an opening to receive the valve stem 2. On the outer end of said valve stem, which is preferably made square or hexagon, is mounted a two pronged lever arm 9, to each end of which is connected the 70 operating cable 10, and in its central part it is provided with an indicator or pointer 9', the utility of which will be readily apparent. Formed on the said plate 5 are a pair of standards 12, or housings, which are internally threaded to receive the set screw 13, 75 each one being provided with a jam nut 14.

The operation of my device is as follows: The set screws 13 are first adjusted in their bearings so that their inner ends will limit the 80 movement of the lever arm 9. In Fig. 1 the position of the said lever arm in full lines being shouldered against the set screw 13, is when the valve is opened to the maximum 85 limit desired to admit the necessary volume of gas to operate the engine running under full load, and the position in dotted lines, also shown as being shouldered against the opposite screw, indicates that the valve is closed sufficient to admit only the minimum amount 90 of gas necessary to operate the engine while running with a reduced load. The operator, being presumably at some distance away from the regulating valve, has simply to draw on, for example the upper strand of the 95 cable to open the valve to its pre-determined limit, see full lines Fig. 1, and in order to shut off the supply he pulls on the lower strand, when the lever arm 9 will be brought into the position shown by dotted lines Fig. 1, and thereby close the valve sufficiently to allow only the minimum amount of gas to flow to the engine.

It will readily be seen that by turning the set screws either inwardly toward each other, or else in the reverse direction away from each other, the distance between their inner ends is correspondingly diminished or increased, and by so doing the movement of the lever arm 9 is limited. This in turn naturally sets up the limitation for the movement of the valve stem 2, and as heretofore

described, governs the quantity of gas being admitted to the engine.

- The secondary adjusting means, provided in the dial plate 5, whereby that member 5 may be turned at an oblique angle to the valve casing 1, as shown in Fig. 2, affords a means for diminishing the movement of the lever arm in the direction of the full open position, without disturbing the set screws, and 10 consequently a reduced amount of gas will flow to the engine at the extreme forward position permitted the said lever than will occur when the dial plate is in alinement with the valve casing, as shown in Fig. 1. Likewise, in the arrangement of parts shown in 15 Fig. 2, on the movement of the lever arm to its reverse limitation, a less amount of gas will flow through the valve to furnish the minimum quantity to the engine.
- 20 In the form shown in Fig. 4 I dispense with the secondary adjusting means, heretofore described, and form the dial plate 5 as an integral part of the valve casing.
- I do not limit myself to the exact construction shown in the drawings, and heretofore 25 described, as various alterations are possible in the detail forms claimed without departing from the fundamental ideas involved. For instance, a solid connection may be made 30 with the lever arm 9 in place of the cable

means here shown, and likewise various forms of adjusting screws may be substituted for those described.

Referring to the cable means for operating the lever arm 9 it is understood that the 35 same will be passed over or around a suitable wheel,—not shown,—and convenient to the operator.

Having thus fully described and shown my invention, what I claim, and desire to secure 40 by Letters Patent, is:

In a valve regulating device, the combination, with the valve, of a dial plate adjustably secured thereto and provided with arcuate slots to allow for said adjustment; a 45 two pronged lever arm secured to the valve stem having an indicator point formed thereon; suitable housings formed at opposite sides of the dial plate; adjustable screw members passing through the housings to 50 limit the movement of the lever arm; and means connected to each arm of the lever for operating the same at a distance.

In testimony whereof, I affix my signature, in presence of two witnesses.

GILBERT R. MILLER.
